CLAIM

The ornamental design for a bucket, as shown and described.

DESCRIPTION

FIG. 1 is a perspective view of the bucket when viewed from the right side, showing my design;

FIG. 2 is a perspective view when viewed from the front;

FIG. 3 is a front elevational view;

FIG. 4 is a side elevational view when viewed from the right side, the left side view being a mirror image;

FIG. 5 is a rear elevational view;

FIG. 6 is a perspective view when viewed from the bottom;

FIG. 7 is a bottom plan view; and,

FIG. 8 is a top plan view.
